(57) **CLAIM**

I claim the ornamental design for "programmable device for a solenoid valve of a watering plant," as shown and described.

DESCRIPTION

FIG. 1 shows a front view of a programmable device; FIG. 2 shows a first lateral view of the device of FIG. 1; FIG. 3 shows a second lateral view of the device of FIG. 1; and, FIG. 4 shows a top view of the device of FIG. 1. The broken line showing the unclaimed portions of the programmable device form no part of the claimed design.
